UNITED STATES PATENT OFFICE.

HARRY Y. ARMSTRONG, OF SPRINGFIELD, MASSACHUSETTS, ASSIGNOR TO PACKAGE MACHINERY COMPANY, OF SPRINGFIELD, MASSACHUSETTS, A CORPORATION OF MASSACHUSETTS.

PACKAGE AND METHOD OF SEALING PACKAGES.

1,215,464.

Specification of Letters Patent. Patented Feb. 13, 1917.

Application filed November 27, 1914. Serial No. 874,136.

To all whom it may concern:

Be it known that I, HARRY Y. ARMSTRONG, a citizen of the United States, residing at Springfield, in the county of Hampden and 5 State of Massachusetts, have invented certain new and useful Improvements in Packages and Methods of Sealing Packages, of which the following description, in connection with the accompanying drawings, is a 10 specification, like reference characters on the drawings indicating like parts in the several figures.

This invention relates to packages and methods of sealing packages.

15 The wrappers are usually secured on packages either by a string tied about the package or by means of some of the common glues or pastes applied to the flaps of the wrapper. In many cases it is undesirable 20 to use a string because of its liability to slip off the package or because of the expense of tying up packages in this manner. It is often undesirable also to use the common adhesives because of their appearance; 25 or their liability to deteriorate under the action of atmospheric changes. Especially in wrapping certain food stuffs are these adhesives objectionable because of undesirable characteristics that are sometimes transferred from them to the goods wrapped. It 30 is also a common practice to wrap certain classes of goods in heavily paraffined paper which is heat sealed in a well-known manner; that is, the overlapping flaps of the 35 wrapper are heated sufficiently to fuse the paraffin on the adjacent layers of paper and are then pressed together and allowed to cool, the wax upon hardening serving to seal the flaps together. But this method is 40 unsatisfactory for many purposes, as for instance in wrapping bread, since the expense of a paraffined paper of the quality required for heat sealing is almost prohibitive for this purpose.

45 The present invention provides a method of sealing package wrappers in an efficient and economical manner and produces a novel package neatly and substantially sealed. The invention will be readily understood from the following description,

reference being made to the accompanying drawings, in which—

Figure 1 is a perspective view showing a package wrapped and ready to be sealed; and

55 Fig. 2 is a similar view showing the package sealed in accordance with this invention.

The drawings show a package comprising an article with a wrapper *w* folded about it in a well-known manner. The method of 60 folding the wrapper will of course vary with circumstances and tastes. In the particular case shown, the wrapper is first folded about three sides of the package. End tucks 1 are then made at opposite ends of 65 the package, leaving at each end two flaps 2 and 3 which later are turned in one over the other, as shown in the drawings, so that they both lie flat against the ends of the package. The wrapper is next tucked in at opposite ends on to the top of the package, 70 as indicated at 4 and 5, thus leaving two flaps 6 and 7 which, when finally folded down, complete the wrapping of the package. One of these flaps 6 is shown in Fig. 75 1, as folded flat on to the top of the package in its final position and the other flap 7 as about to be folded into its final position.

Just before the flap 7 is folded down, a sealing strip of material 8 impregnated or 80 coated with a readily fusible substance, as for instance, paraffin, is laid between the overlapping portions of the flaps 6 and 7. The flap 7 is then folded down, and a hot roller or iron is run over the top of the 85 package pressing the parts 6, 7 and 8 together and melting the paraffin or other fusible substance that is carried by the sealing strip 8. The melted paraffin immediately penetrates and adheres to the flaps 6 90 and 7 and the parts 6, 7 and 8 are held in contact with each other until the paraffin has cooled sufficiently to become hard again when it seals or secures all of these parts together.

95 While other materials than paraffin could be used in the sealing strip 8, I prefer to use paraffin in most cases because it sticks to most papers, is cheap, is readily fusible, can be obtained in either a colorless condi- 100

tion or in colors suitable for use with most wrappers, and is not affected by moisture. For most purposes the sealing strip 8 may consist of a strip of heavily paraffined paper of about the weight used for the heavier grades of self-sealing wrappers. This material will seal successfully a large variety of the papers ordinarily used for wrappers, as for instance, the lighter weight 10 waxed or paraffined papers that are much used in wrapping bread and foodstuffs because of their water-proof properties but which contain too little paraffin to be used satisfactorily as self sealing papers, the so-called "glassine" papers that are much used for wrappers when it is desired to have the article wrapped or an inner wrapper show through the outer wrapper, and tissue or other light weight wrapping papers which are in very general use. A sealing strip of the character described can be inserted automatically by means of simple attachments applied to the wrapping machines and the sealing operation above described can be effected rapidly and efficiently with the aid of well-known hot sealing apparatus. Obviously as many folds may be sealed in this manner as desired.

Having thus described my invention, what 30 I claim as new and desire to secure by Letters Patent of the United States is:

1. A package comprising an article, a wrapper folded about said article and a strip of sheet material carrying a readily fusible substance inserted between the wrapper flaps and secured to the wrapper flaps by said fusible substance.
2. A package comprising an article and a wrapper folded about said article, and a strip of material carrying a readily fusible substance, said strip overlapping both flaps

of the wrapper and being sealed to both of said flaps by the melting and subsequent cooling of said substance while in contact with said flaps.

3. A package comprising an article, a wrapper of lightly paraffined paper folded about said article and a strip of heavily paraffined paper to which both flaps of the wrapper are united by the paraffin carried by said strip.

4. The method of sealing package wrappers which consists in introducing between the overlapping flaps to be sealed a strip of material carrying a readily fusible substance and heating said flaps and material sufficiently to melt said substance and thereby secure said flaps together.

5. The method of sealing package wrappers which consists in overlapping the wrapper flaps to be sealed on a heavily paraffined strip of material, heating said flaps and strip sufficiently to melt the paraffin and allowing the heated parts to cool while pressing the flaps and strip together until the paraffin has hardened.

6. The method of sealing packages wrapped in lightly paraffined paper which consists in inserting between the flaps to be sealed a strip of heavily paraffined paper, simultaneously pressing together and heating said flaps sufficiently to melt said paraffin and cause it to adhere to said flaps, and holding the flaps together until the paraffin has cooled sufficiently to harden.

In testimony whereof I have affixed my signature, in presence of two witnesses.

HARRY Y. ARMSTRONG.
